Filed Apr. 23, 1973, Ser. No. 353,586

Term of patent 14 years

Int. Cl. D29—01
U.S. Cl. D10—106

FIG. 1

FIG. 2

FIG. 3

FIG. 1 is a front elevational view of an electric intruder alarm showing my new design;

FIG. 2 is a side view thereof; and

FIG. 3 is an end view thereof.

The side not shown is similar to the side illustrated in FIG. 2. The end not shown is similar to end shown in FIG. 3 except for the difference in switch configuration.

I claim:

The ornamental design for electric intruder alarm, as shown and described.
